UNITED STATES PATENT OFFICE.

JOHN ANDERSON, OF NEW YORK, N. Y.

COIN-RECEPACLE.

SPECIFICATION forming part of Letters Patent No. 761,435, dated May 31, 1904.

Application filed October 9, 1903. Serial No. 176,399. (No model.)

To all whom it may concern:

Be it known that I, JOHN ANDERSON, a citizen of the United States, residing at New York city, in the borough of Brooklyn, county of 5 Kings, and State of New York, have invented certain new and useful Improvements in Coin-Receiptacles; and I do hereby declare the following to be a full, clear, and exact description of the invention, such as will enable others skilled in the art to which it appertains to make and use the same.

This invention has for its object certain improvements in coin savings-banks whereby the construction thereof is simplified and the 15 security against the extraction of coins therefrom is positively prevented.

Other features of novelty and advantage will hereinafter more fully appear, and in order that the same may be more fully described 20 reference will be had to the accompanying drawings, wherein—

Figure 1 is a central vertical sectional view taken through the device embodying my said invention. Fig. 2 is a transverse sectional view taken at right angles to the section in 25 Fig. 1, and Fig. 3 is a view of the device removed from the coin-receptacle.

In the several views the same letters of reference are employed to designate corresponding parts.

In the embodiment shown in the accompanying drawings, A represents the device applied to a coin-receptacle, preferably rectangular in configuration. Secured within this 35 receptacle A in any suitable manner, such as by the screw *a*, is a coin-chute B. This chute B is approximately V-shaped in general configuration, the upper end of the chute, which is attached to the receptacle A, being in communication with a slot or opening *b*, provided 40 in the wall of said receptacle A, through which is adapted to be passed a coin. This slot *b* is preferably located immediately adjacent one wall of the chute B, the opposite side 45 of said slot being bounded by the guard C, preferably secured in place by the screw *a*. *b*² is an opening left in the lower side of the chute adapted to admit a screw-driver to adjust the screw *a*. Upon the lower open end of 50 said chute B are pivoted a plurality of tumblers

D E. The tumblers D are freely suspended from the point *d*, carried upon the upper wall of the chute-opening, said tumblers being of a length slightly greater than the width of the chute-opening, a stop *d*², forming an extension from the end of the chute, limiting the swinging motion of said tumblers. Beneath these tumblers are similarly suspended a plurality of tumblers E, being side by side upon the point *e*, the rearward motion of these 60 tumblers being limited by the stop *e*². These tumblers E are similar in dimensions to the tumblers D directly above, one set of tumblers being preferably staggered in relation to the others, so as to allow both sets of tumblers D and E to simultaneously close the chute-exit without interference. This arrangement may be clearly seen from Fig. 2; but of course it will be understood that I do not limit myself to any particular arrangement. 70

Now it will be obvious that should a coin be properly inserted in the coin-slot *b* it will enter the chute B, finally resting in the apex thereof. The receptacle is now tilted, causing the tumblers D E to swing clear of the opening of the chute and the coin to slide or roll down through the chute, through the opening therein, and falling into the receptacle A. Any subsequent attempt to extract 80 the coin will be frustrated by the tumblers D E, which will close the chute-opening at all positions of the receptacle except when the receptacle rests upon the left-hand end; but it will be seen that at this position it will be 85 impossible to cause a coin to pass from the receptacle through the chute and out of the slot *b*.

To prevent the escape of a coin while in the chute and to guide the coin while being inserted through the coin-slot *b*, the guard or shield C is provided with an offset *c*, the space between this offset *c* and the adjacent wall of the chute being just wide enough to permit the passage of a coin. 90

While I have shown my invention as embodied in but one form, it will of course be understood that I do not so limit myself, as many changes and modifications might be made in the same, which changes and modifi- 100

cations could be made without departing from the spirit of my said invention. It will also be understood that the device may be employed upon a receptacle of any desired form or design or in any instance where such a device of this character may be desired.

Having thus described my said invention, what I claim, and desire to secure by Letters Patent of the United States, is—

- 10 1. A device of the character described, comprising a chute having coin entrance and exit openings, and interlocking means carried by the lower ends of the chute and removed from proximity to the walls of the device for controlling the passage of coins through the exit-opening thereof, substantially as described.
- 15 2. A device of the character described, comprising a coin-chute having coin entrance and exit openings, and interlocking means pivoted upon the lower ends of the chute and removed from proximity to the walls of the device for preventing the admission of coins to said chute through the exit-opening thereof, substantially as described.
- 20 3. A device of the character described, comprising a chute having coin entrance and exit openings, and a plurality of independently-movable tumblers pivoted upon the upper edge of the exit end of said chute, and a similar set of tumblers arranged beneath the first-mentioned tumblers and pivoted on the lower edge of the exit end of said chute, each said set of tumblers being removed from proximity to the walls of the device, substantially as described.
- 25 4. A device of the character described, comprising a chute having coin entrance and exit openings, a plurality of independently-movable tumblers pivoted upon the upper edge of the exit end of said chute, and a similar set of tumblers arranged beneath and staggered relatively to the first-mentioned tumblers, and pivoted on the lower edge of the exit end of said chute, each said set of tumblers being removed from proximity to the walls of the device, substantially as described.
- 30 5. In a coin - receptacle, the combination with a coin-chute mounted in the upper portion thereof and provided with coin entrance and exit openings, of a plurality of independently-movable tumblers pivoted upon the upper edge of the exit end of said chute, and a similar set of tumblers arranged beneath the first-mentioned tumblers and pivoted on the lower edge of the exit end of said chute, each said set of tumblers being removed from proximity to the walls of the device, substantially as described.
- 35 6. In a coin - receptacle, the combination with a coin-chute mounted in the upper portion thereof and provided with coin entrance and exit openings, of a plurality of independently-movable tumblers pivoted upon the upper edge of the exit end of said chute, and a similar set of tumblers arranged beneath the first-mentioned tumblers and pivoted on the lower edge of the exit end of said chute, each said set of tumblers being removed from proximity to the walls of the device, substantially as described.
- 40 7. In a coin - receptacle, the combination with a coin-chute mounted in the upper portion thereof and provided with coin entrance and exit openings, of a plurality of independently-movable tumblers pivoted upon the upper edge of the exit end of said chute, and a similar set of tumblers arranged beneath and staggered relatively to the first-mentioned tumblers, and pivoted on the lower edge of the exit end of said chute, each said set of tumblers being removed from proximity to the walls of the device, and stops for limiting the movement of said tumblers, substantially as described.
- 45 8. In a coin - receptacle, the combination with a coin-chute mounted in the upper portion thereof and provided with coin entrance and exit openings, of a plurality of independently-movable tumblers pivoted upon the upper edge of the exit end of said chute, and a similar set of tumblers arranged beneath and staggered relatively to the first-mentioned tumblers, and pivoted on the lower edge of the exit end of said chute, each said set of tumblers being removed from proximity to the walls of the device, and stops for limiting the movement of said tumblers, substantially as described.
- 50 9. In a coin - receptacle, the combination with a removable coin-chute mounted in the upper portion thereof and provided with coin entrance and exit openings, of a plurality of independently - movable tumblers pivoted upon the upper edge of the exit end of said chute, a similar set of tumblers arranged beneath and staggered relatively to the first-mentioned tumblers and pivoted on the lower edge of the exit end of said chute, each said set of tumblers being removed from proximity to the walls of the device, and stops for limiting the movement of said tumblers, substantially as described.
- 55 10. In a coin - receptacle, the combination with a coin-chute mounted in the upper portion thereof and provided with coin entrance and exit openings, of a plurality of independently-movable tumblers pivoted upon the upper edge of the exit end of said chute, and a similar set of tumblers arranged beneath the first-mentioned tumblers and pivoted on the lower edge of the exit end of said chute, each said set of tumblers being removed from proximity to the walls of the device, substantially as described.
- 60 11. In a coin - receptacle, the combination with a coin-chute mounted in the upper por-

tion thereof and provided with coin entrance and exit openings, of a plurality of independently-movable tumblers pivoted upon the upper edge of the exit end of said chute, and a similar set of tumblers arranged beneath and staggered relatively to the first-mentioned tumblers and pivoted on the lower edge of the exit end of said chute, each said set of tumblers being removed from proximity to the walls of the device, substantially as described.

12. In a coin - receptacle, the combination with a coin-chute mounted in the upper portion thereof and provided with coin entrance and exit openings, of a plurality of independently-movable tumblers pivoted upon the upper edge of the exit end of said chute, a similar set of tumblers arranged beneath and staggered relatively to the first-mentioned tumblers and pivoted on the lower edge of the exit end of said chute, each said set of tumblers being removed from proximity to the walls of the device, and stops for limiting the movement of said tumblers, substantially as described.

13. In a coin - receptacle, the combination with a coin-chute mounted in the upper portion thereof and provided with coin entrance and exit openings, of a plurality of independently-movable tumblers pivoted upon the upper edge of the exit end of said chute, a similar set of tumblers arranged beneath and staggered relatively to the first-mentioned tumblers and pivoted on the lower edge of the exit end of said chute, each said set of tumblers being removed from proximity to the walls of the device, and stops on the chute for limiting the movement of said tumblers, substantially as described.

14. In a coin - receptacle, the combination with a removable coin-chute mounted in the upper portion thereof and provided with coin entrance and exit openings, of a plurality of independently - movable tumblers pivoted upon the upper edge of the exit end of said chute, a similar set of tumblers arranged beneath and staggered relatively to the first-mentioned tumblers and pivoted on the lower edge of the exit end of said chute, each said set of tumblers being removed from proximity to the walls of the device, and stops for limiting the movement of said tumblers, substantially as described.

In testimony whereof I affix my signature in the presence of two subscribing witnesses.

JOHN ANDERSON.
